UNITED STATES PATENT OFFICE

WALLACE P. COHOE, OF RIVERDALE-ON-HUDSON, NEW YORK, ASSIGNOR TO COHOE PROCESSES, INC., OF NEW YORK, N. Y., A CORPORATION OF NEW YORK
 MACHINE FOR AND METHOD OF DYING CLOTH AND OTHERWISE TREATING TEXTILES

Application filed April 12, 1927. Serial No. 183,035.

This invention relates to a method of and machine for treating textiles with fluids.

In my previous application No. 76,407, filed Dec. 19, 1925, now Patent No. 1,612,698, 5 granted Dec. 28, 1926, I have described a method of and machine for treating a textile with a fluid on one side of the textile by means of a rapidly moving element which, by the phenomenon of skin friction, drives the 10 fluid against the textile and creates a fluid pressure which forces the fluid into, and under certain conditions of operation through, the textile. In said patent I illustrate the invention in connection with a machine in which 15 the rapidly moving element was a roll or a plurality of rolls.

I shall now disclose the invention in connection with a machine in which the rapidly moving element is a non-rotating element and 20 I shall also disclose a machine and method in which I take advantage of the fact that the skin friction may be used not only to create a fluid pressure on one side of the textile, but also to create a suction on the opposite side 25 of the textile, said machine being so designed as to create this fluid pressure and suction with remarkable efficiency and force the fluid through the textile.

The invention will be described in connection with a machine designed primarily for the treatment, such as the washing or dyeing, of an unwoven textile, for instance, lapped material. It is to be understood however, that the following description is merely 35 illustrative of the treatment of other textiles with fluids other than dyes or washing fluids.

The drawings illustrate forms of machines adapted primarily for the treatment of an unwoven textile, although they may be used 40 with other textiles for the purpose of carrying out the process which I have invented all of which will more fully appear from the following description and the accompanying drawings and will be particularly pointed out 45 in the claims.

In the drawings,

Fig. 1 is a diagrammatic section through one of the machines having rolls as the elements which create the fluid stream.

Fig. 2 is a similar view of a machine using a slightly different type of roll.

Fig. 3 is a plan view of the machine illustrated in Fig. 1 showing the mechanism for driving the rolls.

Fig. 4 is a diagrammatic section through a machine of a slightly different form.

Figs. 5 and 6 diagrammatically illustrate types of active or pumping rolls which may be used in the machines.

Fig. 7 diagrammatically illustrates a machine in which the rapidly moving element is a non-rotating body.

The machine illustrated in Figs. 1 to 3 inclusive includes a fluid container which may conveniently consist of 3 parts, namely the bottom 1, the top 2 and the cover 3. The movable elements, in this machine the active or pumping rolls 4, 5, 6, 7, 8 and 9, preferably an even number of rolls, are disposed in sets 70 with one set consisting of rolls 4, 5 and 6 arranged on one side of the textile and the other set consisting of rolls 7, 8 and 9 arranged on the other side of the textile. The textile is shown as a soft unwoven lap 10 supplied 75 from any suitable source which is not shown on the drawings. The lap is fed between two fluid permeable belts 11 and 12, termed aprons, which support it and guide it as it enters the fluid 13 in the container and as it passes between the sets of active rolls. The textile may however, be a woven textile such as cloth in which case the aprons may be dispensed with if desired.

For the purpose of explaining the operation of the machine, the action of one of the active rolls, for example roll 7, will be described in connection with Fig. 1. Each of the rolls is driven at such a rate of speed that it draws with it as it revolves, a stream of fluid which, if the roll were revolving in an open vessel would follow the surface of the roll and revolve with it. If, however, a guard or baffle is placed quite near to the surface of the roll, the stream of fluid which is revolving with the roll will, in effect, be scraped from the surface of the roll and may be directed against the textile. The stream of fluid possesses a large amount of kinetic energy and if it is thus directed against the tex- 100

tile, the speed of the stream will be decreased where it strikes the textile, but a fluid pressure will be created which will cause the fluid to penetrate or pass entirely through the textile. To obtain this result in my machine each of the active rolls is surrounded by a housing which, for purposes of description, may be considered to include the inner wall 14 of the container and the baffle 15. During the usual operation of the machine the container is filled with fluid of such a level that all of the housings are filled and as the roll revolves it creates the stream of fluid just mentioned. The surface 16 of the baffle which is next to the roll is curved concentrically with the surface of the roll and the baffle is so placed in the machine with relation to the roll that there is an exceedingly small space between the face 16 of the baffle and the periphery of the roll. The face 17 of the baffle joins the face 16 in a sharp knife-like edge, extending across the width of the roll and container, which deflects the stream of fluid from its normal path of revolution. As is shown the face 17 of the baffle is spaced from the opposite portion 18 of the inner wall of the container to form an outlet 19 from the housing as well as a passage to direct the fluid stream. The fluid in this passage is under considerable pressure due to the fact that the roll is continually revolving and tending to drive fluid into the passage and this pressure causes the fluid to penetrate the textile. If the pressure is great enough, as it usually is in the commercial operation of the machine, the fluid will pass entirely through the textile. Preferably, the rolls are driven at such a rate of speed that such a pressure is created at the outlet 19 as to force the fluid through the textile quite rapidly and with such force so that the fluid not only contacts with the individual fibers of the textile but is driven into the fibers with the result that a uniform treatment of the textile with the fluid may be obtained.

The inner wall of the housing is preferably given the contour shown on the drawings to assist in the efficient functioning of the machine. For this purpose the wall of the housing is flared so as to be a considerable distance from the periphery of the roll at approximately the point 20 and approaches the roll in a smooth curve to a point 21 where the wall of the container is so close to the surface of the roll so that there is no opportunity for the fluid to form a back current along the housing, that is, at the point 21 the wall of the housing and the surface of the roll are so close together that the fluid stream created by the roll takes up all of the space between the surface of the roll and the wall. The distance between the surface of the roll and the wall of the housing at the point 21 is great enough however, to permit the passage of a fluid stream having sufficient volume to provide

enough fluid to maintain at all times a fluid pressure at the opening 19 and allow for the escape of so much fluid as will pass between the surface of the roll and the curved surface 16 of the baffle.

The fluid enters the housing through the large opening 22 formed by the end 23 of the housing and the curved side 24 of the baffle. As is shown the textile passes across this opening and the fluid enters the housing by passing through the textile. It will readily be understood that when the roll revolves and drives the fluid toward the opening 19 a suction will be created at the opening 22 which draws the fluid through the textile and the opening 22 is large so that the textile is exposed to the suction for quite an appreciable time. This suction is increased by the action of the film of fluid which escapes from the pressure side of the roll through the space between the surface of the roll and the curved surface 16 of the baffle. As the surface of the roll moves from under the end 25 of the baffle, this film of fluid will assist in driving the fluid entering the housing through the opening 22 toward the more narrow part of the space between the surface of the roll and the wall of the housing. From this explanation it will be seen that a single roll creates both a fluid pressure and a suction at spaced points on the same side of the textile and that the suction is created both by the action of the roll in creating the fluid stream which is driven against the textile on the pressure side of the roll and by the action of the film of fluid which escapes from the pressure side to the suction side of the roll between the surface of the roll and the curved surface 16 of the baffle. By changing the size and shape of the baffle and the size and speed of the roll almost any correlation of pressure and suction may be obtained. It is obvious that the slower the peripheral speed of the roll, provided rolls of the same smoothness of surface are used, the less will be the speed and kinetic energy of the fluid stream created and also the greater the space between the surface of the roll and the surface 16 of the baffle the more will be the fluid which escapes from the pressure side of the roll and consequently the less will be the pressure at the opening 19 and the greater will be the suction created by the film of fluid which escapes from the pressure side of the roll into the opening 24 of the housing.

Although the machine may contain only one active roll a plurality of rolls are preferably used and the rolls and housings are preferably so spaced that the area of suction created by one roll is opposite, although not necessarily coextensive with, the area of pressure created by another roll on the opposite side of the textile so that each roll assists another in creating a stream of fluid

passing through the textile. Thus, adjacent rolls on opposite sides of the textile may be considered as working in pairs and the roll 7 may be paired either with roll 4 or with roll 5. In the normal operation of the machine the roll 5 creates a fluid stream exerting pressure on one side of the textile in the opening 26 which pressure forces the fluid through the textile and at the same time the roll 7 creates a fluid stream exerting suction on the opposite side of the textile which tends to suck the fluid through the textile and in this way the rolls of any pair cooperate in creating a stream of fluid passing through the textile. Similarly the roll 7 creates a pressure at the opening 19 and the roll 4 creates a suction on the opposite side of the textile so that the fluid which enters the housing through the opening 22 is forced from the housing through the textile and into the housing surrounding the roll 4. Considering all of the active rolls it will be seen that a continuous stream of fluid passes back and forth through the textile first from one side of the textile and then from the other while the textile is continuously passed across the stream and between each passage through the textile energy is imparted to the stream. The baffles 15 acting conjointly with the wall 14 of the container surrounding the respective rolls separate the inlet and outlet openings into the housing and space the points at which the stream passes back and forth through the textile and also limit the area of application of the suction and pressure created by the rolls. The stream starts with rolls 9 and passes through the textile into the suction side of the housing surrounding roll 6 which roll then imparts energy to the fluid stream and drives it through the textile into the housing surrounding roll 8 which roll in its turn imparts energy to the fluid stream and drives it into the housing surrounding the roll 5 and so on. Thus each roll is revolved at such a rate of speed and in such a direction with relation to the rolls of its set and the rolls of the other set that a fluid pressure is created on one side of the textile and a suction is created on the opposite side of the textile so that a stream of fluid is created and forced through the textile. In a machine of the construction shown in Fig. 1 in which the rolls revolve in the directions indicated by the arrows on them the fluid stream continually moves from one end of the container toward the other end and in order to permit the fluid to return so that it may again pass through the textile the cover of the machine is provided with a passage 27 to provide for the back flow of the fluid. It is possible, although not economical, to prevent the rotation of any one or more of the active rolls or remove any of the rolls from its housing. The remaining rolls will then create the stream of fluid and drive it as previously described.

The textile which is fed to the machine is preferably of such a thickness that it, and its supporting aprons when such aprons are used, freely move through the space 28 provided for them as shown on the drawings. To provide for the easy passage of the textile and aprons through the machine frictionless rollers 29 may be placed on the faces 30 of the baffles and the faces 31 of the wall of the container. The rollers also prevent the leakage of the fluid parallel to the textile or through the textile in the direction of its length from the pressure side of any roll to the suction side by pressing the aprons 11 and 12 toward each other and compressing the textile and by filling the space between the aprons and the faces 30 and 31 of the baffles and container walls. It has been found that rollers situated on the housing in the positions shown in the drawings are sufficient to prevent the escape of fluid parallel to the textile and are also sufficient to provide for the easy movement of the textile and aprons through the machine, but more rollers may be provided at suitable points if desired. Different sized rollers 29 may be used to accommodate textiles of different thicknesses. Thus if a thin textile is run through the machine larger rollers 29 are used to compress the textile and prevent the escape of fluid from any pressure area to any suction area in a direction parallel with the textile or through the textile in the direction of its length. If the combined thickness of the textile and aprons is such that, in their expanded condition after passing between the rollers 29, they fully occupy the space 28 this assists in preventing the leakage of fluid from a pressure space to a suction space.

In case the textile to be treated is an unwoven textile such as lapped material, it is supported and carried through the machine by means of aprons 11 and 12. The apron 11 passes over the feed roller 32 where it meets the textile 10 and the apron 12 passes over the feed roll 33 where it also meets the textile and together the aprons carry the textile through the machine. The textile and aprons are drawn through the machine by means of the press rolls 34 and 35 which not only draw the textile through the machine, but squeeze the surplus fluid from the textile. The roll 35 draws the apron 12 away from the textile and returns the apron to the feed roll 33. The roll 34 returns the apron 11 to the feed roll 32 by means of the idling rolls 36 and 37. The treated lapped material may be removed from the apron 11 at any convenient point but is usually removed from the apron at the roll 34 as is illustrated on the drawings.

The parts of the machine are preferably so arranged that the textile passes through the

machine in a plane, that is, the textile is kept perfectly flat when it is under treatment and does not pass around the active rolls. This is especially desirable in case the textile is unwoven and has to be carried through the machine by the aprons. The plane in which the textile passes through the machine is parallel to the plane determined by the axes of the active rolls of a set so that the textile is equally spaced at all points from any roll adjacent which it passes with the result that the fluid stream is forced against the textile with equal pressure at all points. For this purpose the faces 29 of the baffles 5 and the faces 30 of the wall of the container which form the space or passage 28 are flat and parallel to each other. These faces 29 and 30 of the baffle and container also have a considerable area so that, in addition to preventing the leakage of the fluid from the pressure side of a roll to the suction side the surfaces may support the textile as it passes through the machine. The baffles and housing for the active rolls are also preferably so placed with relation to the passage 28 for the textile that the fluid is driven perpendicularly against the textile which is desirable because it puts no strain on the textile along its length. The textile is guided into the passage by means of the guide rolls 38 and 39 which are preferably mounted in frictionless bearings so that they turn very easily. The guide roll 38 is of such a size and so placed that it takes the textile directly from the feed rolls 31 and 32 and leads it directly into the passage 28 through which it passes through the machine. The guide roll 39 is of such a size and so placed that it takes the textile from the passage 28 through which it is passed through the machine and feeds it to the press roll 34.

The lower press roll 34 is driven from an electric motor 40 which drives a gear 41 which meshes with a gear 42 on the press roll 34. The upper press roll 35 may, if desired, be driven by the gears 43, 44 and 45. Gear 43 meshes with gear 42 and also with gear 44 which in turn meshes with the gear 45 on the upper press roll so that the upper press roll is driven in the correct direction to draw the textile through the machine. Press roll 35 may, if desired, be driven by the gears 43, 44 and 45.

Fresh fluid is fed into the container to compensate for that absorbed by the textile. This fluid is contained in a tank 46 from which it is drawn by the pump 47 and forced by means of pipes 48, 49 and 50 into the container. The pipes 49 and 50 deliver the fresh fluid into pipes 51 and 52 which extend entirely across the machine and have small openings so that the fresh fluid is distributed entirely across the width of the container. Valves 53 permit the fresh fluid to be delivered either at the end where the textile

enters the container or at the end where the textile leaves the container or both, as desired. The pump 47 is driven by means of a belt 54 from the motor 40. The belt 54 drives a pulley 55 to which the plunger of the pump is connected by the crank 56. By means of an adjustable connection, such as the bolt and nut 57, between the crank and the pulley the stroke of the pump may be varied to supply a greater or less amount of fluid. The arrangement for varying the amount of fresh fluid supplied to the container is desirable because a thick textile removes more fluid from the machine than does a thin textile and therefore more fluid must be delivered to the machine when a thick textile is treated than when a thin textile is treated. The fluid which is squeezed from the textile by the press rolls 34 and 35 drips from the lower press roll 34 and is caught in a receiver 58 from which it may either be drawn off or allowed to return to the machine.

Steam or cold water may be admitted to, or withdrawn from, the spaces 59 surrounding the active rolls to control the temperature of the fluid and inlets and outlets 60 are provided for this purpose. The fluid with which the textile is treated may be withdrawn from the container by the outlets 61.

Each set of active rolls may be driven as a unit from gearing in a gear box 62 shown on Fig. 3. The set of rolls 4, 5 and 6 may be driven from shaft 63 on which are mounted bevelled gears 64. A shaft similar to shaft 63 drives bevelled gears 65 which revolve the rolls 7, 8 and 9. The bevelled gears 64 and 65 mesh with pinions 66 which turn short shafts 67 which, through quick detachable universal joints contained in casings 68, drive the shafts 69 which are connected to the spindles 70 of the active rolls. The spindles for the rolls revolve in frictionless bearings 71 which are shown on Fig. 3. Plates 72 on the side of the container and packing nuts 73 prevent the leakage of fluid from the container and allow the active rolls to be removed.

Bearings 74 support the spindles 75 of the feed and press rolls and permit the rotation of these rolls. Bearings in housings 76 support the spindle of the guide roll 38 and permit the rotation of the roll. Bearings and housings similar to the bearings and housings 76 support and permit the rotation of the guide roll 39 but these have not been shown on Fig. 3 in order to simplify the drawing.

The machine shown in Fig. 2 is similar to the machine shown in Figs. 1 and 3, except that the active rolls are not smooth but contain vanes 77. It has been found that by using rolls which have vanes a greater fluid pressure and suction can be obtained than is obtained by the use of smooth rolls having the same peripheral speed, because the vanes 125

are in effect a roughening of the surface of the rolls and cause a greater friction between the rolls and the fluid so that the fluid stream formed by the revolution of the vaned rolls has more kinetic energy than has the fluid stream created by the smooth rolls provided the smooth rolls and the vaned rolls are revolved at the same speed. It is therefore possible to revolve the vaned rolls at a slower speed to obtain a fluid pressure or suction equal to that set up by the smooth rolls. In the case of the vaned rolls the vanes may be of such a length that they do not completely fill the space between the base surface 78 of the roll and the wall of the container and they just clear the face 16 of the baffle. Therefore, as the vaned rolls revolve they create the fluid stream which is deflected by the face 17 of the baffle and passes through the textile as described above with regard to the smooth rolls.

The vanes may have any suitable shape or length. Fig. 5 shows a roll having vanes which are quite like the teeth on gear wheels and gears have been successfully used as active rolls on machines for treating narrow strips of cloth. The roll shown in Fig. 6 has longer vanes than the rolls shown in Fig. 2 and if such a roll were used in the machine shown in Fig. 2 the vanes would completely fill the space between the base surface 78 of the roll and the housing in which case it would be necessary to cut back the face 16 of the baffle to permit the longer vanes to pass.

The machine diagrammatically illustrated in Fig. 4 operates on the same principle as that shown in Fig. 1, but baffles are not used. In this case the adjacent rolls of a set cooperate so that together they form either a fluid pressure or suction on the textile. For purposes of reference the rolls in this type of machine are numbered 79, 80, 81, 82, 83 and 84 of which rolls 79, 80 and 81 compose one set and rolls 82, 83 and 84 compose the other set. Considering the adjacent rolls 82 and 83 of one set, it will be seen that these rolls revolve in opposite directions so that their surfaces at the points 85 are moving in the same direction, that is upwardly, and as each roll creates a fluid stream and draws the fluid with it the streams created by the respective rolls will join and create a fluid pressure on the under side of the textile which will force the fluid through the textile. The rolls 82 and 83 are preferably of such a size and so placed that the distance between the surfaces at the point 85 is less than twice the distance between the surface of either roll and the container at the point 86 so that the volume of the combined fluid streams set up by the rolls 82 and 83 will be more than sufficient to form a fluid stream filling the space and moving between the rolls at the point 85. Therefore, as the two fluid streams join and move be-

tween the rolls at the point 85, the stream at the point 85 is moving very swiftly and more nearly approaches the peripheral speed of, or may even move faster than, the surface of either roll at the point 85 and thus there is no possibility of a back current between the rolls at the point 85 and a fluid pressure is at all times maintained in the space 87 next to the textile. The stream of fluid which passes between the rolls at the point 85 possesses a great amount of kinetic energy and is driven with great force against the textile and has sufficient force to pass through the textile. The walls 88 of the container are preferably curved concentrically with the rolls and join at the point 89 so that the fluid stream set up by each active roll is directed into the space between the rolls at the point 85 which also assists in maintaining the direction of movement of the fluid streams.

The rolls 79 and 80 are revolved in such a direction that they cooperate to create on the textile a suction opposite to the pressure created by the rolls 82 and 83. As the fluid passes from the space 87 through the textile the rolls 79 and 80 pick it up and drive it into the spaces 90 between the rolls and the wall 88 of the container. The rolls 79 and 80 are of such a size and so placed that the distance between the rolls at the point 91 is less than twice the distance between either roll and the wall 88 of the container and therefore all of the fluid which passes between the rolls at the point 91 may easily escape, that is, the combined volume of the passages between the rolls 79 and 80 and the wall of the container at the points 90 is greater than the volume between the rolls 79 and 80 at the point 91 and, therefore no pressure is built up in the spaces 90 which will prevent the rolls from drawing out of the suction space 92 all of the fluid which passes through the textile. Thus considering the rolls 79 and 80 and 82 and 83, it will be seen that the two adjacent rolls of one set, for instance the rolls 82 and 83, revolve in opposite directions and cooperate to produce between them a stream of fluid exerting a fluid pressure on one side of the textile and also cooperate to form a fluid stream passing through the textile; and the rolls 79 and 80 also revolve in opposite directions and cooperate to form between them a stream of fluid exerting a suction on one side of the textile and to form a fluid stream passing through the textile each of the rolls being so revolved with regard to speed of rotation and its position relative to the textile and to the adjacent roll that these results are obtained. When the rolls 79 and 80 revolve in opposite directions the adjacent surfaces of the rolls at point 91 move in the same direction to exert a suction on the textile and likewise when the rolls 82 and 83 revolve in opposite directions their adjacent surfaces at point 85 move

in the same direction to exert a pressure on the textile. If the opposite rolls 80 and 83 are considered as a pair it will be seen that these rolls revolve in the same direction and 5 cooperate with each other to create a fluid stream passing through the textile, the roll 83 creating a fluid pressure over an area on one side of the textile and the roll 80 creating a suction on the other side of the textile. 10 Therefore each roll is revolved at such a rate of speed and in such a direction with relation to the rolls of its set and the rolls of the other set that a fluid pressure is created on one side of the textile and a suction is created 15 on the opposite side of the textile so that a stream of fluid is created and forced through the textile.

The active rolls 81 and 84 are preferably similar to the other active rolls and are so 20 revolved that they cooperate with the rolls 80 and 83 in the same way as do the rolls 79 and 82. Thus the roll 81 cooperates with the adjacent roll 80 to form a fluid pressure in the space 93 and the roll 84 cooperates with 25 the adjacent roll 83 to create a suction in the space 94 and the adjacent rolls 81 and 84 cooperate with each other to form a fluid stream passing through the textile. All of 30 the rolls cooperate to create a fluid stream passing back and forth through the textile first from one side of the textile and then from the other while the textile is continuously passed across the stream and each roll imparts energy to the stream between 35 each passage through the textile. The rolls space the points at which the stream passes back and forth through the textile and limit the areas of application of the suction and pressure.

40 The ends of the container adjacent the outside pairs of rolls are especially designed to assist in creating the fluid stream. For this purpose the wall 95 of the container is spaced a considerable distance from the roll 82 so 45 that a reservoir of the fluid is provided in the space 96 and the wall of the container at the point 97 is substantially straight so that the stream of fluid created by the roll 84 is directed against the textile.

50 The textile 10, which is shown in Fig. 4 without the supporting aprons, is preferably led between the sets of rolls in a plane parallel with the planes determined by the axes of the active rolls of either set and perpendicular to the plane determined by the axes of the active rolls of any pair. Guide rolls 38 and 39 similar to those described in connection with Fig. 1 are used for this purpose. These guide rolls are of such a size and so placed 55 that they feed the textile between the active rolls and remove it therefrom as is described in connection with Fig. 1. The textile is preferably of such a thickness that it almost entirely fills the space between the active rolls 60 of any pair of rolls and thus prevents the

escape of any large amount of fluid parallel with the textile. If the textile touches the rolls it is possible that the friction will heat the textile. In this type of machine however, it is preferable not to have the textile touch the rolls and therefore the textile passes between the opposite rolls in a plane substantially at right angles to the plane determined by the axes of the rolls so that the textile is adjacent the rolls for as short a distance 70 as possible and the rolls are preferably revolved at such a rate of speed that they carry with them a film of fluid between the surface of the roll and the textile. Thus, the textile rides over the rolls on a film of fluid. The 75 speed at which the rolls must be revolved to maintain this film of fluid on the surface of the rolls depends upon the viscosity of the fluid and the permeability of the textile, as well as the thickness of the textile, but ordinarily any speed of revolution of the rolls which will create the fluid stream through the textile is sufficient to maintain the film of fluid between the surface of the roll and the textile. This fluid film which passes between the surface of the roll and the textile leaves the surface of the roll in the suction space and assists in creating the suction as has previously been described in connection 80 with Fig. 1. Thus, the films of fluid between 85 the surface of the roll 79 and the textile and between the surface of the roll 80 and the textile are thrown away from the surface of the respective rolls as the surfaces move away from the textile, that is, the fluid of the 90 films is thrown into the suction space 92, but as the fluid films are moving in the direction of revolution of the rolls they meet and assist in creating the suction in the space 92 and thus assist in drawing the fluid from 95 the pressure space 87 into the suction space 92 and thus assist in creating the stream of fluid passing through the textile. Since the textile is not supported by baffles in a machine such as is shown in Fig. 4, the textile will 100 bulge slightly from the pressure space 87 toward the suction space 92 and will also bulge from the pressure space 93 to the suction space 94, but this bulging may be prevented in large measure by keeping the textile taut while it is passing through the machine. 105

In the machine shown in Fig. 7 the movable elements are continuous belts 98 and 99 which move in contact with the fluid and create the fluid stream. As in all of the machines shown, the stream of fluid is parallel to the surface of the moving element; in the case of the machines shown in Figs. 1, 2 and 4 the stream is concentric with the active rolls 110 and in Fig. 7 the fluid stream is parallel to the surface of the belt. Baffles 100 are so placed in the machine that they lie in the path of the fluid stream and as the stream strikes the baffles a fluid pressure is created which 115 120 125 130 135

may, if the belts are moving fast enough, drive the fluid through the textile 10. The baffles also serve to direct the fluid against the textile. For this purpose the baffles are preferably of such a size that one end of each baffle lies close to the moving belt and the other end of the baffle lies close to the textile and the faces of the baffles are such that they perform their function of deflecting the fluid stream and directing it against the textile with as little reduction of the energy of the stream as is possible. Baffles substantially like those shown in Fig. 7 are deemed satisfactory. Such baffles lie entirely across the space between the textile and the adjacent belt and have curved forward faces 101 to deflect the fluid stream and direct it against the textile.

When the belts are moving fast enough to give the fluid stream sufficient kinetic energy, the fluid will pass entirely through the textile and the baffles on opposite sides of the textile are preferably staggered so that one baffle directs the fluid stream through the textile in one direction and the next baffle causes the fluid stream to pass through the textile in the other direction. Each baffle is preferably so spaced from the adjacent baffle of its set on the same side of the textile that the fluid is exposed between the adjacent baffles to the action of the belt on that side of the textile for a sufficient length of time to impart sufficient energy to the fluid to drive it through the textile when it strikes the next baffle. Therefore, in the case of the machine shown in Fig. 7, as in the cases of the machines shown in Figs. 1, 2 and 4 the fluid stream passes back and forth through the textile and energy is imparted to the stream after each passage of the fluid through the textile.

It will be understood that as either belt passes a baffle and the fluid stream is deflected from the surface of the belt by the forward face 101 of the baffle, a suction will be created in the space 102 in back of the baffle and this suction will assist in drawing the fluid through the textile. Thus each baffle acting conjointly with the adjacent belt creates both a fluid pressure and a suction on the textile, the pressure and suction being on the same side of the textile and at spaced points and also adjacent baffles on opposite sides of the textile simultaneously create a suction and a pressure on opposite sides of the textile.

Any number of baffles may be used but preferably only enough are used and they are so spaced that the pressure and suction areas are arranged for the most effective creation of the fluid stream and its passage back and forth through the textile.

The belts 98 and 99 are moved by means of the pulleys 103 which may be driven in any suitable manner as, for instance, by a

modified gear box similar to that shown in Fig. 3. Also the belts may be moved in either direction but they are preferably moved in the same direction and opposite to the movement of the textile as shown in Fig. 7. When the belts are moved in the direction shown, the fluid will move from right to left with the belts along the center line of the machine and will move from left to right with the belts along the top and bottom of the machine and in this way a circulation of the fluid will be obtained. The speed of the belts depends upon such factors as the thickness of the textile, the viscosity of the fluid, etc. Obviously the thinner the textile the easier the fluid will pass through it and the less will have to be the speed of the belts.

The space between the upper and lower parts of each belt is filled in by the casings 104 so that the amount of space in the machine which the fluid may occupy is decreased to the end that as little fluid as possible need be used in the machine. Steam or cold water for heating or cooling the fluid may be admitted into or withdrawn from the interior of the casing through the openings 60 and the fluid may be withdrawn from the container through the pipe 61. The ends 105 of the casings are preferably curved concentrically with the pulleys 103 and lie very close to the surface of the pulleys so that little or no fluid is between the ends 105 and the pulleys because it is not desired to form a fluid stream in this space, the formation of which would consume energy. For the same reason the sides 106 of the casing lie closely to the belts and the sides also serve to back up the belt where the belt passes next to a baffle.

The textile is fed into the machine by means of the feed rolls 32 and 33 and is withdrawn from the machine by means of the press rolls 34 and 35. The guide rolls 38 and 39 are so placed that they take the textile from the feed rolls and deliver it to the press rolls and maintain the textile while it is passing through the machine in a plane mid-way between the belts 98 and 99.

Although particular and preferred forms of the machine of the present invention have been described and preferred methods of operating the machines to carry out the process which I have invented have been described, it is recognized that modifications in the machine and process may be made and therefore it is distinctly to be understood that the invention is to be construed as broadly as the limitations in the claims taken in conjunction with the prior art may allow.

I claim:

1. In a method of treating a textile with a fluid the steps which include passing the textile between two rolls in contact with the fluid and revolving the rolls at such rates of speed and at such directions that they cooperate to

create a stream of fluid passing through the textile.

2. In a method of treating a textile with a fluid, the steps which include creating a pressure of the fluid on one side of the textile and simultaneously creating a suction on the opposite side of the textile by means of revolving rolls.

3. In a method of treating a textile with a fluid, the steps which include passing the textile between two rolls in contact with the fluid and revolving the rolls at such a rate of speed and at such directions that one roll creates a fluid pressure on one side of the textile 15 and the other roll creates a suction on the opposite side of the textile whereby fluid is forced through the textile.

4. In a method of treating a textile with a fluid, the steps which include passing the textile between two opposite rolls in contact with the fluid and revolving the rolls at such a rate of speed and in such directions that one roll creates a fluid pressure on one side of the textile and the other roll creates a suction on the 25 opposite side of the textile whereby the pressure and suction force the fluid through the textile.

5. In a method of treating a textile with a fluid, the steps which include passing the textile between two opposite rolls in contact with the fluid and revolving the rolls in the same direction and at such rates of speed that one of the rolls creates a fluid pressure over the area of one side of the textile and the other 35 roll creates a suction on the opposite side of the textile whereby the pressure and suction force the fluid through the textile.

6. In a method of treating a textile with a fluid, the steps which include passing the textile between sets of rolls in contact with the fluid and revolving each of the rolls at such a rate of speed and in such a direction with relation to the rolls of its set and the rolls of another set that a stream of fluid is created 45 and forced through the textile.

7. In a method of treating a textile with a fluid, the steps which include passing the textile between sets of rolls in contact with the fluid and revolving each of the rolls at such a rate of speed and in such a direction with relation to the rolls of its set and the rolls of another set that a fluid pressure is created 50 on one side of the textile and a suction is created on the opposite side of the textile to force the fluid through the textile.

8. In a method of treating a textile with a fluid, the steps which include passing the textile with one side adjacent to a plurality of rolls and so revolving each of the rolls 60 with regard to speed of rotation and its position relative to the textile and to an adjacent roll that adjacent rolls create between them a stream of fluid exerting pressure on the textile.

9. In a method of treating a textile with

a fluid, the steps which include passing the textile with one side adjacent to a plurality of rolls and so revolving each of the rolls with regard to speed of rotation and its position relative to the textile and to an adjacent roll that adjacent rolls create between them a stream of fluid exerting suction on the textile.

10. In a method of treating a textile with a fluid, the steps which include passing the textile with one side adjacent to two rolls and revolving the rolls in opposite direction at a speed sufficient to create between them a stream of fluid exerting pressure on the textile.

11. In a method of treating a textile with a fluid, the steps which include passing the textile with one side adjacent to two rolls and revolving the rolls in opposite directions at a speed sufficient to create between them a stream of fluid exerting suction on the textile.

12. In a method of treating a textile with a fluid, the steps which include passing the textile between sets of rolls in contact with the fluid and revolving each of the rolls at such a rate of speed and in such a direction with relation to the adjacent roll of another set that a stream of fluid is created and forced through the textile.

13. In a method of treating a textile with a fluid the steps which include passing the textile between sets of rolls and revolving each of the rolls at such a rate of speed and in such a direction with relation to the adjacent roll of another set that a fluid pressure is created on one side of the textile and a suction is created on the opposite side of the textile to force the fluid through the textile.

14. In a method of treating a textile with a fluid, the steps which include passing the textile between sets of rolls in contact with the fluid and so revolving the adjacent rolls of a set that said adjacent rolls cooperate to create a stream of fluid passing through the textile.

15. In a method of treating a textile with a fluid, the steps which include passing the textile between sets of rolls in contact with the fluid and so revolving the adjacent rolls of a set that the adjacent surfaces of the respective rolls move in the same direction and cooperate to create a stream of fluid passing through the textile.

16. In a method of treating a textile with a fluid, the steps which include passing the textile between sets of rolls in contact with the fluid and so revolving the adjacent rolls of a set that the adjacent surfaces of the respective rolls move in the same direction and cooperate to exert a fluid pressure on the textile.

17. In a method of treating a textile with a fluid, the steps which include passing the textile between sets of rolls in contact with

the fluid and so revolving the adjacent rolls of a set that the adjacent surfaces of the respective rolls move in the same direction and cooperate to exert a suction on the textile.

5 18. In a method of treating a textile with a fluid, the steps which include passing the textile between sets of rolls in contact with the fluid and so revolving the adjacent rolls of each set that said adjacent rolls cooperate to create a stream of fluid passing through the textile.

10 19. In a method of treating a textile with a fluid, the steps which include passing the textile between sets of rolls arranged in series with one roll of each pair on each side of the textile and contacting with the fluid, and so revolving the adjacent rolls that they cooperate to create a stream of fluid passing through the textile.

15 20. In a method of treating a textile with a fluid, the steps which include passing the textile between sets of rolls arranged in series with one roll of each pair on each side 25 of the textile and contacting with the fluid and so revolving the adjacent rolls of each set and pair that a fluid pressure is created on one side of the textile and a suction created on the opposite side of the textile to create 30 a stream of fluid passing through the textile.

21. In a method of treating a textile with a fluid, the steps which include forming a stream of the fluid and forcing the stream by pressure through the textile first from one 35 side of the textile and then from the other while continually passing the textile across the stream.

22. In a method of treating a textile with a fluid, the steps which include forming a stream of the fluid and forcing the stream through the textile first from one side of the textile and then from the other and imparting energy to the stream between each 45 passage of the fluid through the textile while continually passing the textile across the stream.

23. In a method of treating a textile with a fluid, the steps which include forming a stream of the fluid and forcing the stream by pressure through the textile first from one side and then from the other at spaced 50 points while continually passing the textile across the stream.

24. In a method of treating a textile with a fluid the steps which include forming a stream of fluid and forcing the stream through the textile first from one side and then from the other at spaced points and imparting energy to the stream between each 60 passage of the fluid through the textile while continually passing the textile across the stream.

25. In a method of treating a textile with a fluid the steps which include providing a baffle and a movable element, and moving

said element in the fluid with sufficient speed to draw with it by friction sufficient fluid to form a fluid stream, and so interposing the baffle in the path of said stream that the fluid is directed against the textile.

70 26. A machine for treating a textile with a fluid including a fluid container, two rolls within the container adapted to contact with the fluid, means adapted to pass the textile between the rolls, and means adapted to rotate the rolls at such rates of speed and at such directions that said rolls cooperate in creating a stream of fluid through the textile.

75 27. A machine for treating a textile with a fluid including a fluid container, two rolls within the container adapted to contact with the fluid, means adapted to pass the textile between the rolls and means adapted to rotate the rolls at such rates of speed and in such directions that one roll creates a fluid pressure on one side of the textile and the other roll creates a suction on the opposite side of the textile.

80 28. A machine for treating a textile with a fluid including a fluid container, two opposite rolls within the container adapted to contact with the fluid, means adapted to pass the textile between the rolls, and means adapted to revolve the rolls in the same direction at such rates of speed that said rolls cooperate 85 in creating a stream of fluid passing through the textile.

85 29. A machine for treating a textile with a fluid including a fluid container, two opposite rolls within the container adapted to contact with the fluid, means adapted to pass the textile between the rolls, and means adapted to revolve the rolls in the same direction at such rates of speed that one roll creates a fluid pressure on one side of the 100 textile and the other roll creates a suction on the opposite side of the textile.

105 30. A machine for treating a textile with a fluid including a fluid container, sets of rolls within the container adapted to contact with the fluid, means adapted to pass the textile between the sets of rolls, and means adapted to revolve each of the rolls at such a rate of speed and in such a direction with relation to the rolls of its set and the rolls 110 of another set that a stream of fluid is created and forced through the textile.

115 31. A machine for treating a textile with a fluid including a fluid container, sets of rolls within the container adapted to contact with the fluid, means adapted to pass the textile between the sets of rolls, and means adapted to revolve each of the rolls at such a rate of speed and in such a direction with relation to the rolls of its set and the rolls of another set 120 that a fluid pressure is created on one side of the textile and a suction is created on the opposite side of the textile to force the fluid through the textile.

125 32. A machine for treating a textile with

a fluid including a fluid container, a plurality of rolls within the container adapted to contact with the fluid, means adapted to pass the textile through the container with one side adjacent to said rolls, and means adapted to so revolve each of the rolls with regard to speed of rotation and its position relative to the textile and to an adjacent roll that the adjacent rolls create between them a stream of fluid exerting pressure on the textile.

33. A machine for treating a textile with a fluid including a fluid container, a plurality of rolls within the container adapted to contact with the fluid, means adapted to pass the textile through the container with one side adjacent to said rolls, and means adapted to so revolve each of the rolls with regard to speed of rotation and its position relative to the textile and to an adjacent roll that the adjacent rolls create between them a stream of fluid exerting suction on the textile.

34. A machine for treating a textile with a fluid including a fluid container, two rolls within the container adapted to contact with the fluid, means adapted to pass the textile through the container with one side adjacent to said rolls, and means adapted to revolve said rolls in opposite directions and at such a rate of speed that the rolls create between them a stream of fluid exerting pressure on the textile.

35. A machine for treating a textile with a fluid including a fluid container, two rolls within the container adapted to contact with the fluid, means adapted to pass the textile through the container with one side adjacent to said rolls, and means adapted to revolve said rolls in opposite directions and at such a rate of speed that the rolls create between them a stream of fluid exerting suction on the textile.

36. A machine for treating a textile with a fluid including a fluid container, sets of rolls within the container adapted to contact with the fluid, means adapted to pass the textile between the sets of rolls, and means adapted to revolve each of the rolls at such a rate of speed and in such a direction with relation to the adjacent roll of another set that a stream of fluid is created and forced through the textile.

37. A machine for treating a textile with a fluid including a fluid container, sets of rolls within the container adapted to contact with the fluid, means adapted to pass the textile between the sets of rolls, and means adapted to revolve each of the rolls at such a rate of speed and in such a direction with relation to the adjacent roll of another set that a fluid pressure is created on one side of the textile and a suction is created on the opposite side of the textile to force the fluid through the textile.

38. A machine for treating a textile with

a fluid including a fluid container, sets of rolls within the container adapted to contact with the fluid, means adapted to pass the textile between the sets of rolls, and means adapted to so revolve the adjacent rolls of a set that the adjacent surfaces of the respective rolls move in the same direction and cooperate to create a stream of fluid passing through the textile.

39. A machine for treating a textile with a fluid including a fluid container, sets of rolls within the container adapted to contact with the fluid, means adapted to pass the textile between the sets of rolls, and means adapted to so revolve the adjacent rolls of a set that the adjacent surfaces of the respective rolls move in the same direction and cooperate to exert a fluid pressure on the textile.

40. A machine for treating a textile with a fluid including a fluid container, sets of rolls within the container adapted to contact with the fluid, means adapted to pass the textile between the sets of rolls, and means adapted to so revolve the adjacent rolls of a set that the adjacent surfaces of the respective rolls move in the same direction and cooperate to exert a suction on the textile.

41. A machine for treating a textile with a fluid including a fluid container, sets of rolls within the container adapted to contact with the fluid, means adapted to pass the textile between the sets of rolls, and means adapted to so revolve the adjacent rolls of each set that said adjacent rolls cooperate to create a stream of fluid passing through the textile.

42. A machine for treating a textile with a fluid including a fluid container, sets of rolls arranged in pairs within the container adapted to contact with the fluid, means adapted to pass the textile between the pairs of rolls, and means adapted to so revolve the adjacent rolls that they cooperate to create a stream of fluid passing through the textile.

43. A machine for treating a textile with a fluid including a fluid container, sets of rolls arranged in pairs within the container adapted to contact with the fluid, means adapted to pass the textile between the pairs of rolls, and means adapted to so revolve the adjacent rolls of each set and pair that a fluid pressure is created on one side of the textile and a suction is created on the opposite side of the textile to create a stream of fluid passing through the textile.

44. A machine for treating a textile with a fluid including a container for the fluid, a roll within the container adapted to contact with the fluid, means adapted to pass the textile adjacent to said roll, means adapted to revolve the roll at such a rate of speed as to create a suction and a fluid pressure on the textile and means adapted to limit the area of application of the suction and pressure.

45. A machine for treating a textile with

- a fluid including a container for the fluid, a roll within the container adapted to contact with the fluid, means adapted to pass the textile adjacent to said roll, means adapted to revolve the roll at such a rate of speed as to create a suction and a fluid pressure on the textile and a baffle partially surrounding the roll and limiting the area of application of the pressure and suction. 5
- 10 46. A machine for treating a textile with a fluid including a container for the fluid, a roll within the container adapted to contact with the fluid, means adapted to pass the textile adjacent said roll, means adapted to revolve the roll at such a rate of speed as to create a stream of fluid parallel to the surface of the roll, and means adapted to deflect said fluid stream and direct it against the textile. 15
- 20 47. A machine for treating a textile with a fluid including a container for the fluid, a roll within the container adapted to contact with the fluid, a housing for the roll having openings through which the fluid may pass into and out of said housing, means adapted to pass the textile over said openings and means adapted to revolve the roll at such a rate of speed that the fluid is drawn through the textile into the housing through one of the openings and forced from the housing 25 through the textile through another of the openings. 30
- 35 48. A machine for treating a textile with a fluid including a container for the fluid, a roll within the container adapted to contact with the fluid, a housing for the roll having openings through which the fluid may pass into and out of said housing one of said openings being larger than another, means adapted to pass the textile over said openings, and means 40 adapted to revolve the roll at such a rate of speed and in such a direction that fluid is drawn through the textile into the housing through said larger opening and forced from the housing through the textile through another opening. 45
- 50 49. A machine for treating a textile with a fluid including a container for the fluid, a roll within the container adapted to contact with the fluid, a housing for the roll having openings one of which is larger than another and through which the fluid may pass into and out of the housing, said housing being spaced from the roll and formed to provide a passage partially around the roll between the openings and being flared to meet said larger opening, means adapted to pass the textile over said openings, and means adapted to revolve the roll in such a direction and at such a speed that the fluid is 55 drawn through the textile into the housing through said larger opening and forced from the housing through the textile through another opening. 60
- 65 50. A machine for treating a textile with a fluid including a container for the fluid, a plurality of rolls within the container on alternate sides of the textile, means adapted to pass the textile between the rolls, means adapted to revolve the rolls at such rates of speed that each roll creates a suction and a fluid pressure on the textile and means to so place the areas of suction and pressure that the area of suction created by one roll is opposite to the area of pressure created by another roll, whereby a stream of fluid 70 is forced through the textile. 75
- 80 51. A machine for treating a textile with a fluid including a container for the fluid, a plurality of rolls on alternate sides of the textile, a housing for each roll having openings through which the fluid may pass into and out of said housing, means adapted to pass the textile over said openings, means adapted to revolve each roll at such a rate of speed that fluid is drawn through the textile into each housing through one of the openings and forced from the housing through the textile from another of the openings, the housings being so positioned that the opening through which the fluid is drawn 85 into one housing is opposite the opening through which the fluid is forced from another housing. 90
- 95 52. A machine for treating a textile with a fluid including a fluid container, two rolls within the container for contact with the fluid and having their axes parallel to each other, means for passing the textile between the rolls in a plane substantially at right angles to the plane of said axes and means 100 for rotating the rolls at such rates of speed and in such directions that one roll creates a fluid pressure on one side of the textile and the other roll creates a suction on the opposite side of the textile. 105
- 110 53. A machine for treating a textile with a fluid including a fluid container, sets of rolls within the container for contact with the fluid and having the axes of the rolls parallel to one another, means adapted to pass the textile between the sets of rolls in a plane parallel to the plane of the axes of the rolls of a set, and means adapted to revolve each of the rolls at such a rate of speed and in such a direction with relation to the rolls of its set that a stream of fluid is 115 forced through the textile. 120
- 120 54. A machine for treating an unwoven textile with a fluid including a fluid container, a roll within the container for contact with the fluid, means adapted to pass the textile adjacent said roll including a fluid permeable apron for supporting the textile, and means adapted to revolve the roll at such a rate of speed that the fluid is forced through the textile. 125
- 130 55. A machine for treating an unwoven textile with a fluid including a fluid container, two rolls within the container for contact with the fluid, means adapted to pass the

textile adjacent said rolls including a fluid permeable apron for supporting the textile, and means adapted to revolve the rolls at such rates of speed and in such directions that said rolls cooperate in creating a stream of fluid directed against the textile.

56. A machine for treating an unwoven textile with a fluid including a fluid container, two rolls within the container for contact with the fluid, means adapted to pass the textile adjacent said rolls including a fluid permeable apron for supporting the textile, and means adapted to revolve the rolls at such rates of speed and in such directions that said rolls cooperate in creating a stream of fluid through the textile.

57. A machine for treating an unwoven textile with a fluid including a fluid container, two rolls within the container for contact with the fluid, means adapted to pass the textile between said rolls including a fluid permeable apron for supporting the textile, and means adapted to revolve the rolls at such rates of speed and in such directions that said rolls cooperate in creating a stream of fluid passing through the textile.

58. A machine for treating a textile with a fluid including a container for the fluid, a movable element within the container adapted to contact with the fluid, means adapted to move said element with sufficient speed to draw with it by friction sufficient fluid to form a fluid stream, a baffle situated in the path of said fluid stream and adapted to deflect said fluid stream and to draw it against the textile, and means adapted to pass the textile through the container adjacent to said baffle.

59. A machine for treating a textile with a fluid including a container for the fluid, a set of rolls within the container adapted to contact with the fluid, means adapted to rotate said rolls with sufficient speed to draw with them by friction sufficient fluid to form a fluid stream, means adapted to pass the textile between the rolls, a baffle having a face concentric with one of the rolls and placed close to the rolls, said baffle having another face tangent to the roll and situated to direct the fluid stream created by the roll against the textile.

60. A machine for treating a textile with a fluid including a container for the fluid, a set of rolls within the container adapted to contact with the fluid, means adapted to rotate said rolls with sufficient speed to draw with them by friction sufficient fluid to form a fluid stream, means adapted to pass the textile between the rolls, a baffle having a face concentric with one of the rolls and placed close to the roll and having another face tangent to the roll and situated to direct the fluid stream created by the roll against the textile to form a pressure area, a second baffle having a face concentric with the other roll

and placed close to the roll, said second baffle being situated to create a suction area opposite the said pressure area.

In testimony that I claim the foregoing, I have hereunto set my hand this 19th day of 70 March, 1927.

WALLACE P. COHOE.
